UNITED STATES PATENT OFFICE

EUGENE A. HARDIN, OF DETROIT, MICHIGAN

PILE

Application filed October 13, 1927. Serial No. 225,912.

This invention relates to piles and method of setting piles. More particularly the invention has to do with piles which consist in part of wood and in part of concrete.

The use of piles consisting of wood and concrete has been heretofore proposed. It has been proposed to drive the wooden piles into the ground with the top of the wooden pile below the surface of the ground, and then pour in wet concrete above the pile to form a concrete section. Some disadvantages are present in such a construction because the nature of the joint between the wooden pile and the wet concrete can not be accurately ascertained. Also when piles are driven in close proximity, the compression of the ground may cause an adjacent pile in which the concrete is not fully set to jack-knife, or buckle. This construction is expensive due to the fact that a steel tube or mould must be used for the wet concrete which cannot be removed but remains under the surface of the ground.

The present invention contemplates a pile and method of setting the same which overcomes the objections incident to the practice of pouring wet concrete. Accordingly the invention contemplates a composite pile consisting in part of wood and in part of pre-formed concrete. By utilizing a preformed concrete part, the same can be connected or joined to the adjacent wooden part above the surface of the ground so that the nature of the joint is fully ascertained. Moreover, the concrete being fully preformed, the danger of causing the pile to buckle or jack-knife is avoided.

I am aware of the fact that it has been proposed to use piles constructed entirely of concrete which are then driven into the ground. This has not worked out to the best advantage because the length of the concrete pile must be within certain defined limits because too long a pile will waver and shatter to pieces when being driven. Moreover, a concrete pile is more expensive per given unit of length than a wooden pile. According to the present invention, however, the pile is entirely preformed, but is a composite one consisting of wood and pre-

formed concrete. This materially reduces the cost of the pile, and moreover, the concrete section can be within the limits of length so that the probability of shattering the concrete portion while driving the same is avoided.

In the accompanying drawings:

Fig. 1 is a view showing a pile composed of wood sections and a section of preformed concrete and also showing how the connection is made between a wood and concrete section. 60

Fig. 2 is a view of a joint showing the use of a metal socket at the joint between a wood section and concrete section. 65

Fig. 3 is a modified form showing a different arrangement for effecting the connection between the concrete section and the wooden section, with the use of an additional metal socket. 70

Figs. 4 and 5 are views depicting further modified forms of metal sockets.

The pile is made up of a requisite number of wooden sections or poles 1, and these poles may be connected together by a metal ring 2 in the usual manner. The uppermost wooden pole is to be attached to a concrete section 3, this concrete section being the uppermost portion of the pile. 75

For the purpose of making the connection, the uppermost wooden pole may be cut away, as at 4, and the concrete section may be formed with a recess or socket which fits over the cut-away portion of the pole. Preferably the depth of the cut in the pole is substantially equal to the thickness of the walls around the recess in the concrete section, so that the extreme end of the concrete section does not project outwardly from the pole. The concrete section may be provided with outwardly flared walls 5 to obtain greater thickness in the concrete, thus securing greater strength. 80

The relation between the cut-away portion on the uppermost wooden pole and the socket 95 in the concrete section is such as to space the lowermost end of the concrete section, as shown at 6, from the shoulder 7 of the cut-away portion in the pole. This insures weight supporting contact between the pole 100

and concrete section between the extreme end of the pole and the base of the recess, or in other words, at the point referenced 8. By doing this, the possibility of splitting either the wooden pole or the concrete section by weight at the points 6 and 7 is avoided. The spacing between points 6 and 7 is shown in a somewhat exaggerated manner.

In setting a pile of this construction, one or more wooden sections are driven into the ground in the usual manner. The number of wooden sections will of course vary with varying conditions, and in some cases, even one length only will be used. When the last of the wooden piles is driven into the ground, and at about the position with respect to the surface of the ground, as shown in Fig. 1, the ground being referenced 9, a fully preformed section of concrete is placed over the wooden pile. This section of concrete is to form the uppermost end of the pile. It will be understood that the wooden piles are driven into the ground with any of the suitable automatic hammers now used, and such hammer is placed on top of the concrete pile, and the whole pile is driven the proper distance into the ground.

The concrete section is preferably of reinforced construction and it may include various arrangements of spiral steel reinforcements and longitudinally extending reinforcements. However, in so far as this invention is concerned, any reinforced concrete section can be used. In Fig. 2 there is shown a connection between the wood and concrete sections which utilizes a metallic socket member 10. This socket member may be in the form of a keep ring disposed between the overlapping sections of wood and concrete. The ring may be fixed to the concrete section by casting the concrete over the ring.

A similar arrangement is shown in Fig. 4, but here the ring 11 is provided with a series of ribs 12. These ribs may be provided in the socket member by any desirable method and bite into the wood and materially prevent any twisting as between the wood and concrete section. The ring 15, shown in Fig. 3 is provided with struck in portions 16 which bite into the wood and which leave recesses 17 for the concrete.

A further modified form is shown in Fig. 5. In this form the concrete section is provided with longitudinally extending steel reinforcing bars 18. The arrangement is such that these bars make contact with the ring 19 and they may be welded to the ring before the pouring of the concrete. In this construction the ring is very securely tied to the concrete section and, if desirable, this ring also can be provided with portions for biting into the wood.

These connecting rings or socket members provide for strengthening the connection between the wooden pole and the concrete sec-

tion so as to materially eliminate the possibility of buckling of the joint. However, in some cases, it may be found that such a ring is not necessary, and in this case it may be eliminated as shown in Fig. 1.

In following the invention, and using a preformed concrete section, the connection between the wooden pile and the concrete section is made entirely at a time and in a position so that the nature and strength of this connection can be fully ascertained. This position is preferably above the surface. Inasmuch as the concrete section is preformed, the danger of buckling the joint, which may arise by compression of the earth when piles are driven into the earth in close proximity is avoided. Sometimes it may be necessary to pull the pile out of the ground, and the use of the connecting rings will assure withdrawal of the wooden pile.

Claims:

1. A pile, comprising one or more sections of wood, a section of preformed concrete provided with a socket into which the uppermost end of the wooden section fits, and a metal ring disposed between the walls of the socket and the said end of the wooden section, said metal ring having means biting into the wood.

2. A pile, comprising one or more sections of wood, a section of preformed concrete provided with a socket into which the uppermost end of a wood section fits, and a metal ring disposed between the walls of the socket and the said end of the wooden section, said metal ring having struck in portions which bite into the wood and which provide recesses on the outside of the ring into which the concrete interlocks.

In testimony whereof I affix my signature.

EUGENE A. HARDIN.
